Attorney

UNITED STATES PATENT OFFICE.

GEORGE F. BORKMAN, OF SALT LAKE CITY, UTAH.

RADIORECEIVER.

Application filed December 4, 1924. Serial No. 753,844.

My invention relates to receivers for radios and like devices, and has for its object to provide an economical and efficient amplifying receiver by which the sounds are transmitted clearer and reproduced without the discordant metallic sound now commonly heard through devices of similar kinds.

These objects I accomplish with the device illustrated in the accompanying drawings in which similar letters and numerals of reference indicate like parts throughout the several views, and as described in the specification forming a part of this application and pointed out in the appended claims.

In the drawings in which I have shown the best and most substantial embodiment of my invention, Figure 1 is an edge view of the device, with the horn and enclosing case omitted. Figure 2 is another view of the same at right angles to the positions shown in Figure 1. Figure 3 is a plan view of the device, and Figure 4 is a side and plan view of one of the magnets. Figure 5 is an end view of the armature and an edge view of the diaphragm with the connecting means.

One of the special features of my invention is to build up the permanent magnet by a plurality of flat bars A rigidly fastened together by the bolts 6 and nuts 7. An insulating strip C is fastened across the curved portion 1 of the built-up permanent magnet by the same bolts 6 being passed through its end portions. An electromagnet is mounted between the poles 2 and 3, and 4 and 5 of the permanent magnet. The said electromagnet consists of a coil D with the ends thereof fastened to the contact posts 8 and 9 which are secured on the insulating strip C. The said coil D is wound on a spool or armature E having a flat pivoted core 10 which is parallel with the median plane of said permanent magnet and movable on its pivot by the electrical impulses received by said coil. One edge of said core is extended, as shown at 10, and to which is secured the diaphragm 11 by the connecting pin 12. A cap member F carries the horn, which is not shown, and also a cylindrical casing or cup G which is secured to said cap member F, and within which cup member the magnets are fastened. The armature 10 is pivoted and

poised in a neutral normal position between the north and south poles of the permanent magnet, which magnet, as before explained, may be made of one or a plurality of said steel forms, shown in Figure 4. The electromagnetic impulses force the armature from neutral position, and this action allows the permanent magnet to get a closer magnetic connection with the armature and quicker action in its movements and impulses to the diaphragm, as well as to intensify the impulses. There is a local magnetic flux existing between the bifurcated ends 2 and 3, and 4 and 5. This magnetic flux has also a direct harmonious action on the armature 10, causing it to smooth out the sounds. When armature 10 is energized by incoming impulses it is disturbed from its neutral position and there is some noise and foreign distortion takes place in getting back to its required position, this flux has a distinct bearing on eliminating this condition.

Having thus described my invention and its operation I desire to secure by Letters Patent and claim:—

1. A receiver comprising one or more flat steel magnets of the horseshoe type, having one end portion bifurcated and bent to form two parallel spaced apart poles; and other similarly shaped magnets secured thereto with the bifurcated portions opposed in direction; an electromagnet mounted between the prongs of said bifurcated portions; a poised core mounted therein; a diaphragm substantially parallel with the planes of the first mentioned magnets and operatively connected with the poised core of the electromagnet.

2. A receiver comprising a magnet of the horseshoe type made up of steel lamina; one leg of said magnet bifurcated; an electromagnet mounted between the bifurcations of the magnet; said electromagnet having a poised core at right angles to the plane of the first-mentioned magnet; and a diaphragm mounted in the plane of the first-mentioned magnet; with means connecting said poised core and said diaphragm.

In testimony whereof I have affixed my signature.

GEORGE F. BORKMAN.
